UNITED STATES PATENT OFFICE.

EVERETT N. GOULD, OF JAMESTOWN, NEW YORK.

METALLIC DOOR.

1,013,934.

Specification of Letters Patent.

Patented Jan. 9, 1912.

Application filed March 15, 1911. Serial No. 614,657.

To all whom it may concern:

Be it known that I, EVERETT N. GOULD, a citizen of the United States, residing at Jamestown, in the county of Chautauqua and State of New York, have invented new and useful Improvements in Metallic Doors, of which the following is a specification.

This invention relates to metallic doors and to a method of manufacturing the same.

10 One of the objects of the invention is to provide a simple, inexpensive and thoroughly fire-proof door in which no rivets or other fastening devices are used to connect the separate parts together and wherein the 15 welds will be concealed.

A further object of the invention is the provision of a door which may be constructed by first securing together the vertical and horizontal stiles, attaching the 20 panels and necessary molding and finally bending the door into shape and filling the space between its separated sides with a suitable refractory material.

A further object of the invention is the 25 provision of a door of this character having its separate parts including the panels, top and bottom rails or stiles and the cross stiles welded together in such a manner that the blisters of the welds occur upon the inside 30 so that a perfectly smooth door is produced which can be opened without grinding out and buffing the blisters after they occur upon the outside.

Further objects of the invention will appear as the following specific description is 35 read in connection with the accompanying drawings, which form a part of this application, and in which:

Figure 1 is an elevation of the door. Fig. 40 2 is a longitudinal section on the line 2—2 of Fig. 1. Fig. 3 is a transverse section on the line 3—3 of Fig. 1. Fig. 4 is a transverse section showing the position of the door before being bent into shape. Fig. 5 is 45 an enlarged detailed sectional view of the upper sill filler. Fig. 6 is an enlarged section of the lower stile and pillow.

Referring more particularly to the drawings, 1 and 2 represent the vertical stiles, 50 3 and 4 the top and bottom stiles respectively and 5 the cross stile. The stile 1 is constructed of separate sections 6 and 7 both of which are formed with lateral flanges 8 adapted to overlap each other when the 55 parts of the stile 1 are brought together and at their opposite sides are provided with

substantially L-shaped flanges 9, the legs 10 of which extend parallel to each other and in parallel lines with the sides of the stile. The stile 2 comprises a single strip of metal 60 which is provided on opposite sides with L-shaped flanges 11 and 12 which, when the stile is bent into form as will hereinafter be described, are brought into similar relation to each other as are the L-shaped flanges of 65 the stile 1. The stiles 3 and 4 are each constructed of separate sheets of metal having the L-shaped flanges 13 and a filler 14 which is substantially U-shaped in cross section and has its base or bottom seated in between 70 the separate parts of the stile. The cross stile comprises separate members 15 and 16 each having L-shaped flanges 17. All of the stiles have their L-shaped flanges so constructed as to form abutting shoulders 18 for 75 the metallic panels 19 which are secured to the flanges with their edges abutting the shoulders by means of spot welds, shown in dotted lines at 20. The filler member 14 for the upper stile is provided with inwardly 80 projecting tongues or fingers 21 which are adapted to engage slots 22 in the inverted U-shaped filler 23, the sides of the latter member being sufficiently resilient to permit the same to snap over the fingers. The filler 85 14 of the lower stile closes the space which is formed between the panels and the sides of the stile members and the upper stile member closes the space at the upper end of the door. The space is preferably filled with 90 asbestos or other similar refractory material 24, and a molding 25 is secured between the shoulders 18 and the panels. This molding may be secured in place by any suitable kind of fastening device or may be welded in 95 place with an oxygen or acetylene torch.

In the manufacture of the device the top and bottom stiles are secured to the vertical stiles and the panel 19 spot welded to the flanges thereof while the stile 2 is in the position shown in Fig. 4. The molding is placed in position while the parts are as shown in Fig. 4 and the cross stile spot or torch welded into place. The stile 2 is then bent upon the lines 27—28 which causes the 105 flanges 8 of the sections 6 and 7 of the stile 1 to overlap each other. These flanges are then spot-welded together, and the filler 14 of the lower stile is then inserted and spot welded into position, with the blisters occurring upon the inside and the filler member 14 of the upper stile is also placed in po- 110

sition and has the blisters occurring upon the inside. Prior to the insertion of the 5 filler for the upper stile the space between the sides of the door is filled with a refractory material. After the filler for the upper stile has been placed in position the inverted filler member is snapped into position and the door is completed.

Having thus described the invention, what 10 I claim as new is:—

1. A method of constructing a metallic door which consists in forming one of the vertical stiles in two parts, forming the opposite stile of a single part, securing to the 15 single part stile and to the parts of the two-part stile the cross stiles and panels and bending the single part stile so as to overlap the parts of the double part stile, and finally connecting the parts of said double part 20 stile.

2. A method of forming a metallic door which consists in forming one of the stiles of separate parts, forming the opposite stile of a single part, securing panels and cross 25 stiles to said vertical stiles, bending the single part stile to bring the panels parallel with each other and to overlap the parts of the double part stile, and finally connecting the parts of the double part stile.

3. A method of forming a metallic door which consists in forming one of the stiles of separate parts, forming the opposite stile of a single part, securing panels and cross 30 stiles to said vertical stiles, bending the sin-

gle part stile to bring the panels parallel 35 with each other and to overlap the parts of the double part stile, and finally connecting fillers in certain of the cross stiles.

4. A method of constructing a metallic door which consists in forming one of the vertical stiles of two members and the opposite stile of a single member, connecting 40 said vertical stiles with cross stiles and panels by welding, the blister of which is arranged on the inside, bending said single 45 part stile to bring the cross stiles and panels into parallel relation, and welding the parts of the double part stile together.

5. A method of constructing a metallic door which consists in forming one of the vertical stiles of two members and the opposite stile of a single member, connecting 50 said vertical stiles with cross stiles and panels by welding, the blister of which is arranged on the inside, bending said single 55 part stile to bring the cross stiles and panels into parallel relation, welding the parts of the double part stile together, filling the space formed between the stiles and panels with a refractory material, and securing 60 filler members to hold the refractory material in place to close said space.

In testimony whereof I affix my signature in presence of two witnesses.

EVERETT N. GOULD.
